UNITED STATES PATENT OFFICE.

WILLARD B. FEATHERSTONE, OF WASHINGTON, DISTRICT OF COLUMBIA.

BUILDING CONSTRUCTION.

1,109,214.

Specification of Letters Patent. Patented Sept. 1, 1914.

Application filed July 2, 1909. Serial No. 505,696.

To all whom it may concern:

Be it known that I, WILLARD B. FEATHERSTONE, a citizen of the United States, residing at Washington, in the District of Columbia, have invented certain new and useful Improvements in Building Construction, of which the following is a specification.

My invention relates to the class of construction known as reinforced concrete, and has for its objects, to simplify the work of erecting such buildings, and make them stronger, and safer, and more permanent. I accomplish these results by employing the novel kind of forms, and reinforcing steel, and methods of placing, described in this specification and shown in the drawings, in which:

Figure 1 shows a beam and a portion of another beam and two columns in section. Fig. 2 is a perspective view of the beam shown in Fig. 1. Fig. 3 is part of an elevation of a building. Fig. 4 is a horizontal section through pilasters and curtain-wall. Fig. 5 is a vertical section at $z-z$, Fig. 6. Figs. 6 and 7 show longitudinal sections of beams. Fig. 8 shows a beam divided lengthwise. Fig. 9 shows a curtain-wall slab with sill attached. Fig. 10 shows a method of attaching a base-capital at the junction of column and beam.

In the drawings, A^1 and A^2 , Fig. 3, are hollow columns supporting the hollow beam shells C^1 , C^2 , etc. These in turn support the columns A^7 and A^8 , all of which column and beam shells are suitably reinforced and afterward filled with concrete.

In constructing a building, the column shells A^1 and A^2 are set in position on the footings with the curtain-wall slab B between them. They are then partly filled with concrete and the beam shells C^1 , C^2 , etc., hoisted into position. Additional reinforcement is now placed over the column from beam to beam, and bars H , Fig. 3 inserted in the concrete in the lower column and extending into the hollow space in the upper column A^7 . The combined base-capital K , Fig. 8, is then placed in position and anchored as shown in Fig. 10.

Fig. 1 shows an improved form of reinforcement, and also bracing for the column shells A^4 and A^5 , and the beam shells C^3 and C^4 .

Figs. 2, 5, 6, 7 and 8 show other views and modifications of the beam shell C^3 . The concrete ribs or braces P , Figs. 1, 5, 6, 7 and 8

serve to stiffen the shells during handling and also to increase the bond between the old and new concrete. The reinforcing bars T , Figs. 3, 5, 6, 7 and 10 are anchored in the beam shells C^5 , C^6 , etc., but are so disposed that the fresh concrete can surround portions of them. The wire netting or other minor reinforcement as R , Figs. 5, 6 and 7 is contained within the substance of the shell itself to stiffen its thinner portions.

In Fig. 4 is shown a method of joining the curtain-wall slabs B and b to the pilasters A^2 and A^6 , fresh concrete being poured in at N and N^1 after the projections N^2 have been inserted in the grooves N^3 .

Fig. 8 shows a horizontal member or beam-shell divided lengthwise to save weight and to facilitate handling.

In Fig. 9 the curtain-wall slab B' , which has been molded in one piece with the sill B'' , is reinforced with the wire netting B and stiffened by the ribs P' .

It will be seen that by my new method of building construction it is possible to do away entirely with wooden or metal forms, thus saving a great deal of time and expense. It is not necessary however, to have these tubular parts or shells made of Portland cement concrete with the customary aggregates, as any material which will adhere to the fresh concrete and can be conveniently made and shipped in the necessary lengths and sizes, is suitable for the purpose and sometimes more desirable, as a greater variety of surface finishes can be provided.

I claim:

1. A building having its framework constructed of preformed concrete shells each comprising a mold substantially equal in length to the beam or column of which it forms a part, transverse projections on the inner surfaces of the shells, longitudinal reinforcements partially embedded by the projections and extending beyond the ends of the shells, for the purpose of bonding or tying the adjoining beams or columns, and concrete filling the shells and embedding the remainder of the reinforcements.

2. A structural unit composed of a preformed concrete shell comprising a mold substantially equal in length to the unit of which it forms a part, and having transverse interior projections, longitudinal reinforcements passing through and partially embedded by the projections, and extending beyond the ends of the shell for the purpose

of facilitating union with like units or shells, and concrete filling the shell and embedding the remainder of the reinforcements.

3. A girder composed of a preformed concrete shell of approximately U-shaped section and substantially equal in length to the girder, and having transverse ribs P, reinforcing rods or the like T, CR, passing through the ribs and extending beyond the 10 ends of the shell, and concrete filling the shell.

4. A girder form comprising a one-piece

concrete shell of approximately U-shaped section, and substantially equal in length to the length of a girder unit, projections, P, P, 15 on the inner surface of the shell, reinforcements partially embedded in the projections and extending beyond the ends of the shell.

WILLARD B. FEATHERSTONE.
